STABILIZED SUPPORT

Charles J. Drueding, New Orleans, La.

Application November 15, 1949, Serial No. 127,497

16 Claims. (Cl. 248—182)

1

The present invention relates to improvements in a stabilized support which operates under gravity and has for an object to provide a device of this kind which includes a platform which will remain horizontal under all conditions. It may be used in conjunction with any device requiring such a platform for its operation. It may also be used as a norm of the horizontal to determine angles and to assist in the direction of objects to destinations.

Briefly, this objective is realized by mounting a rod or cylinder vertically in such manner that it is ultimately supported by a gimbal and by equalizing the weight of a weight fixedly attached to said rod or cylinder below the point of support or axis of said rod or cylinder by supporting a weight or weights around or inside the rod or cylinder in such manner that the additional weight above the axis is not supported by said rod or cylinder insofar as its working upon the rod or cylinder is concerned. As will be hereinafter noted, the additional weight or weights above the axis of support is or are ultimately supported by a gimbal ring separate from but related to the gimbal ring supporting the vertical rod or cylinder.

A mere balance, of course, is insufficient to maintain a horizontal platform as any force or friction would cause it to leave the horizontal position and remain in its new position until again altered by a subsequent force or friction. The gimbals may have some pendulous action of their own. The greater portion of the weight forming the rod, cylinder, sleeve and their attachments could be placed below the line of the gimbals' axis.

Gimbals are used in the device (1) for the purpose of achieving a degree of initial stability in supporting the vertical rod or cylinder; and (2) for the purpose of supporting the additional weight or weights about or within the vertical rod or cylinder in such manner that such weight or weights form no integral or attached part of the rod or cylinder.

With the foregoing and other objects in view, the invention will be hereinafter more fully described and more particularly pointed out in the appended claims.

In the drawings, in which the same parts are denoted by the same reference numerals throughout the several views,

Referring more particularly to the drawings and especially to Figures 1 to 6, inclusive, 20 indicates an outer gimbal ring rotatably mounted on two pins 21 disposed 180 degrees apart and which are in turn supported by fixed brackets 22. The brackets 22 may be mounted upon any suitable supporting platform which carries the entire device.

A gimbal ring 23 of smaller diameter than the gimbal 20 is disposed therein and is rotatably mounted on two shafts 24 which in turn are mounted on the outer gimbal 20. The shafts 24 extend through the gimbal 23 and project inwardly therebeyond and at their inner free ends rotatably support an inner gimbal 25 which is of less diameter and is disposed inwardly of the gimbal 23. The longitudinal axes of the shafts 24 are disposed at an angle of 90 degrees to that of the pins 21. The shafts 24 are mounted in bearings 26 on the gimbals 20 and 23. Alternatively, gimbals 23 and 25 could be fixed to shafts 24 rotatably mounted in gimbal 20.

A ring 27 smaller in diameter than the gimbal 25 is supported from gimbal 23 by four rigid supporting rods 28 which are all secured by welding or the like to the inner surface of the gimbal 23, and by adjusting wires 29. One end of each wire is secured to the ring 27 by welding or the like and the opposite end of each is anchored to a stem 30 of an adjusting screw which is threadedly carried by a plug 31 mounted in the opposite end portion of the supporting rods 28. The end portions of the adjusting wires 29 may be wound around the stem 30 of the screws for adjusting ring 27.

A gimbal 32 smaller in diameter than ring 27 is rotatably supported on two shafts 33 which are mounted on the ring 27. A ring 34 smaller in diameter than the gimbal 32 is supported by four rods 35 which in turn are mounted on the gimbal 32 and are positioned 90 degrees apart.

The lower end portion of a vertically extending rod or cylinder 36 screw-threadedly receives a weight 37. A skirt or hollow rod 38 surrounds the intermediate portion of the rod 36 and four rigid braces 39 which can be in the form of rods have their lower ends secured to the outer surface of the lower end portion of the skirt 38 by rivets or the like 39a and have their upper end portions secured to the inner faces of the gimbal 25 by welding or the like. The intermediate portion of the rod 36 is hollow as indicated at 40 and has a screw threaded socket 41 disposed above and communicating with the hollow portion 40. The diameter of the socket 41 is less than that of the hollow portion 40 thereby providing an annular downwardly facing shoulder 42.

A rod supporting member 43 has a screw threaded shank 44 received by the socket 41 of the rod 36 and a conical point 45 which rests in a bearing 46. The bearing 46 is mounted within a cup 47 which is held in the horizontal axis by four wires 48. The lower end of each wire 48 is attached to a respective pin 49 carried by the cup 47 and the wires extend upwardly and outwardly through suitable passages in the rod 36 and the upper end portion of each wire 48 is anchored to a spool portion 50 of an adjusting screw about which it is adapted to be wound. Each adjusting screw in addition to the spool portion 50 comprises a head 51 carried by the free end of the spool and knob 52 disposed at the opposite end of the adjusting screw, a stem 53 carried by the knob and an enlarged screw threaded portion 54 disposed between the spool 50 and the stem 53.

An interiorly threaded plug 55 is mounted in the upper end portion of the skirt 38 and receives the screw threaded portion 54 of the adjusting screw. The skirt 38 tapers upwardly and inwardly and carries on its inner surface adjacent its upper end portion a bushing 56 which engages a ring 57 carried by or formed integral with the

rod 36 adjacent the bearing 46 in order to prevent point 45 from jumping out of bearing 47.

The weight 37 has mounted thereon as by welding or the like four brackets 58 which are substantially U-shaped and the connecting portion of each bracket has an elongated slot 59 in which is mounted a weight adjusting means 60 comprising a plurality of weights 60a in the form of heavy washers held between the head of a bolt 60b and the U-shaped member 58 by a nut 60c carried by the bolt 60b and frictionally engaging the inner surface of the U-shaped member 58. An adjustable screw 61 having a weighted head 61a is threadedly mounted in each bolt 60b for effecting additional changes of the moments of inertia. A lock nut 61b is provided for holding each screw 61 in adjusted position. The weights 60a may be adjusted along the slot 59 to equalize the distribution of the weight 37 in order to alter the moments of inertia. A pair of fins 62 intersecting at a 90 degree angle are supported by the lower end portion of the weight 37 and depend therefrom.

A sleeve or hollow rod 63 surrounds the upper end portion of the rod 36 and is supported by the rods 35. The lower edge of the sleeve 63 is notched as at 64 to receive the rods 35. The upper end of the sleeve 63 is closed and four vertically extending legs 65 have their lower end portions connected to the upper end portion of the rod 36 and extend upwardly through suitable openings in the closed end of the sleeve 63. A horizontally disposed instrument receiving platform 66 is supported by the upper end of the legs 65.

A screw threaded pin 67 extends through a suitable screw threaded opening in the head of the sleeve 63 and extends downwardly to have its lower end portion received by a cylindrical bore 68 in the upper end portion of the rod 36. The lower end of the pin 67 has a ball 69 detachably mounted thereon by cooperating screw threads or the like. The outside diameter of the ball is slightly less than the inside diameter of the cylindrical bore 68 of the rod 36 in order to prevent binding but to effect a loose connection between the sleeve 63 and the rod 36. The pin 67 has an enlarged head 70 at its upper end by which the pin may be screwed into and out of the head of the sleeve 63 so that the pin may be properly adjusted.

The outer surface of the sleeve 63 has mounted thereon, as by welding or the like, four brackets 72 which are disposed 90 degrees apart. The brackets 72 are substantially U-shaped and the connecting portion of each has an elongated slot 73 therein in which is mounted a weight adjusting means comprising a plurality of weights 74a in the form of heavy washers held between the head of a bolt 74b and the U-shaped member 72 by a nut 74c carried by the bolt 74b and frictionally engaging the inner surface of the member 72. An adjustable screw 75 having a weighted head 75a is threadedly mounted in each bolt 74b for effecting additional changes of disposition of weight. A lock nut 75b is provided for holding each screw 75 in adjusted position. The weights 74a may be adjusted in the slot 73 to equalize the distribution of the weight of the sleeve 63 and/or to alter the moments of inertia.

In the use of the device, since the gimbals 23 and 25 are both rotatably mounted on the shafts 24, they will have the same direction of rotation. Consequently, vertical rod or cylinder 36, 75 which is supported by the gimbal 25 by means of

the connecting arms 39 and the supporting mechanism 43 to 57, will have the same direction of rotation as upper sleeve 63, which is supported by gimbal 23 by means of arms 28 and supporting mechanism 29, 27, 34, 35 and 33. Movement of the entire device within gimbal 20 in a direction of ninety degrees to the direction of rotation of gimbals 23 and 25 could be made possible inasmuch as the axis of rotation of gimbal 20 is at a ninety degree angle to the axis of gimbals 23 and 25 and inasmuch as gimbal 20 could be designed of sufficient diameter to accommodate passage of the entire device within it.

When there is movement of the platform 66, the gimbal action of gimbal 20 in one direction and of gimbals 23 and 25 in the other direction would tend to prevent transmission of the movement of the mechanism supported by the gimbals. Because of friction in the gimbal bearings, force will be transmitted to the supported mechanism. When the center of gravity of the rod or cylinder and sleeve is placed below the line of the axis of the gimbals it is not necessary to increase the moments of the gimbals below the axis since they would be largely stabilized by the weight of the rod and sleeve and attachment braces 39 and skirt 38 would give some pendulous action to the supporting gimbal. This could be offset by weighting above the supporting gimbal if desired.

However, experimentation may indicate that some increase in the moments below the line of the axis would be advisable. Since the positions of conical point 45 and the sleeve support 32 may be changed with reference to the axis of the gimbals various combinations may be tried in order to determine which would be the most suitable under experimentation. It is assumed that the gimbals would be of the finest construction and very sensitive. The design of the supported mechanism is such that the tendency of the rod 36 to leave the vertical is halted or largely halted by the action of the sleeve 63 and its attachments.

Reference is made to the device as exemplified by Figures 1 to 6, inclusive. Reference is here made to the fact that the conical point 45 can be lowered to below the line of the gimbal axis 21 or raised above the line of the gimbal axis 21 by means of struts 48 and that the sleeve support ring 32 may be raised or lowered below or above the line of axis 21 by means of wires 29. Assume that conical point 45 is at the center of the line connecting 21 and that the support for the sleeve 32 is lowered to a point below the conical point 45, and that the weight or moments below conical point 45 is such that the rod and sleeve with attachments constitute a pendulum greater than above conical point 45.

Whenever an external force which would tend to move the platform 66 from the horizontal is applied to the supported means for the brackets 22, the motion imparted to the brackets is transmitted through the pins 21 to the gimbal 20. The movement is then transmitted from the gimbal 20 through the other gimbals and their mountings to the conical point 45 of the rod 36. The movement is also transmitted through the rods 28 and wires 29 to the gimbal 32 and the sleeve 63 which is supported by the gimbal 32. The force transmitted tends to move the gimbal 32 in an arc about point 45 as the center so that as one half of the gimbal 32 swings downwardly the other half swings upwardly and carries the

sleeve 63 with it to raise a portion of the sleeve and move it from the vertical with reference to the rod 36. Friction due to the ball 69 would tend to lift the rod 36 as a portion of the sleeve moves upwardly along the rod. The friction at 69 and the inertia of the sleeve 63 and rod 36 with its weight 37 will resist this moving force and dissipate the force which would otherwise be transmitted to the platform 66. The inertia of the gimbals and the friction between the gimbals and their mountings and any pendulous movement of the gimbals, the skirt 38 and the braces 39 will offer resistance to the transmission of the external force to the platform 66.

The function or purpose of the loose play between the pin 67 and the rod 36 is to prevent binding or jamming of these parts which might prevent them assuming a vertical position again after the external force has been removed. However, the play in pin 67 could be eliminated without the loss of its function of preventing binding by the following means. For example, as shown in Figure 2A, a partial ball bearing socket 36b within the cylindrical bore 68 in the upper end of rod 36a would prevent any upward motion of ball bearing 69a, screwed on the lower end of pin 67 and would therefore prevent any upward movement of the sleeve 63 about the rod 36a. Accordingly, the only way the rod or cylinder 36a could act as a pendulum would be by its lifting the weight of sleeve 63 or by the sleeve 63 lifting the weight of rod or cylinder 36a. The partial ball bearing socket 36b could be adjusted at any point within the cylindrical bore 68 within the rod or cylinder 36a by means of four adjusting screws 36c fitting through vertical slots 36d in the wall of cylindrical bore 68 into the ball bearing socket 36b.

Of course, care must be taken in the design of the ball bearing and ball bearing socket to insure a very slight clearance between them. Otherwise, the weight of the sleeve 63 would be supported by the rod or cylinder 36 rather than by the gimbal 23.

In all cases, the inertia of sleeve 63 considered in relation to the inertia of weight 37 and its attachments in relation to the action of pin 67, plus the necessity of lifting or moving the counterbalancing weight of the sleeve 63 and the friction hereinabove referred to, could prevent the rod or cylinder 36 from deviating from the horizontal plane of gimbal 25. When conical point 45 is placed below the line of axis 21 any movement of platform 66 from the horizontal would result in force being transmitted through the gimbals which would tend to move conical point 45 in an arc around the center of the line of axis 21. The force would tend to move the rod away from its position in the same direction of the sleeve. The inertia of the rod or cylinder and parts would resist the force. The simultaneous tendency lifting the sleeve with its connections would tend to lift the rod or cylinder as indicated above.

In both cases, where the conical point is at the line of the axis 21 or below the line of 21 the sleeve would tend to climb the rod or cylinder and increase the moments upwards along the line of the axis of the rod or cylinder and also transfer weight upwards along the rod or cylinder. This assumed action would lessen any pendulous action of the combined rod or cylinder, and the sleeve. The tendency of the sleeve to climb along the rod would be halted by pin 68 and ball bearing 69a acting on 36b, 36c, 36d.

A finely constructed bearing 46 will cause little friction. The combined inertia of the sleeve and rod would tend to stabilize the gimbals. It is not believed that sufficient force would be transmitted through the gimbals to throw the rod or cylinder from the vertical. Any liquid would react against any movement of the rod or cylinder and the sleeve. Should some slight deviation take place the rod or cylinder would quickly return to its original position and force the gimbal to a horizontal position. The sleeve would also return to its original position.

In order to disturb the rod and sleeve the center of inertia would be raised. If they are to be displaced, and if disturbed tend to return to their original position. In all events such possible movement or deviation would be very slight and momentary. When platform 66 is accelerated in an upward arc friction in the gimbal bearings tend to rotate the gimbals. When either the sleeve support 32 or conical point 45 or both are lowered to a position beneath the line of axis 21 the force transmitted through the gimbals would tend to raise and rotate them in an arc around their common center. Any pendulous tendency of rod and sleeve would be affected by friction at 45 due to action of skirt 38.

With the liquid adaptation applied the buoy 136 would act to assist in maintaining the rod or cylinder vertically. In liquid, considerable use could be made of damping devices.

All through the above descriptive matter pertaining to how the device operates it is necessary to point out that platform 63 is included as a part of the rod or cylinder. Since the positions of conical point 45 and the sleeve support 32 may be changed with reference to the axis of the gimbals, various combinations may be tried out under experimentation in order to determine which arrangement would be most suitable.

Referring to the modification shown in Figures 7 to 10, inclusive, 76, 77 and 78 indicate gimbals similar to the gimbals 20, 23 and 25, respectively. The outer gimbal 76 can be rotatably mounted on the two pins 21 in the same manner that the outer gimbal 20 is mounted.

A skirt 80 is supported in concentric relation to the gimbal 78 by four arms 81 each of which has one end portion attached to the outer face of the lower end portion of the skirt and its opposite end portion attached to the gimbal 78, as by welding or the like. A bearing 82 having an upper concave surface is supported within the upper end portion of the skirt 80 by four rods 83, one end of each of which is connected as by welding or the like to the bearing and its opposite end portion extends through a suitable opening in a ring 84 to terminate in an eyelet 85 which receives one end of an adjusting wire 86. The opposite end of each wire 86 terminates in an eyelet 87 which is pivotally received by a pin 88 mounted on one end portion of a socket member. The opposite end portion of the socket member has a socket 89 therein, the side wall of which has a threaded opening through which extends a threaded set screw 90 engaging in an annular groove 91 in the cylindrical smooth surfaced portion 92 of an adjusting screw. Each adjusting screw has a threaded portion 93 which is received by an interiorly threaded bushing 94 mounted in a suitable opening in the upper end portion of the skirt 80. Each adjusting screw has a knurled head 95.

A cup 96 is disposed within the skirt 80 and has extending upwardly therefrom a conical pointed 75

member 97 and the cup 96 is supported by four arms 98 which extend downwardly and outwardly through suitable openings in the intermediate portion of the skirt 80. The lower end portion of each arm 98 is adjustably connected to one end portion of an arm 99 by a slot and screw connection 100. The opposite end portion of each arm 99 is connected to the gimbal 77 in any suitable manner as by welding or the like.

10 A bearing 101 having a lower concave surface for the reception of the pointed member 97 is connected to one end portion of each of four arms 102. The arms extend downwardly and outwardly through the same openings in the skirt 80 through 15 which the arms 98 extend and the opposite end portions of the arms 102 extend upwardly and inwardly and are secured to the outer surface of the lower end portion of a sleeve 103 which surrounds a vertically extending rod or cylinder 104. The 20 rod 104 extends upwardly through an opening 106 in the sleeve 103.

The platform 66 is supported by the rod 104 in the same manner as illustrated in the form of the invention shown in Figures 1 to 5. The wall of the opening 106 of the sleeve 103 has four conical shaped contact members 107 disposed at about 90 degrees apart and extending into the opening 106 and into contact with the cylinder 104.

25 The lower end portion of the rod 104 has a screw threaded socket 108 which receives the screw threaded portion 109 of a rod supporting member having a conical point 110 received by the bearing 32. A collar 111 is mounted on the lower end portion of the rod 104 and has attached thereto by screws or the like 112 four arms 113 spaced apart about 90 degrees. These arms 113 extend downwardly and outwardly and their lower end portions are adjustably attached to the upper end portions of arms 114 by slot and screw connections 115. Weights 116 are supported by the arms 114 at their lower ends.

30 The operation of the modification shown in Figures 7 to 10, inclusive, is similar to that described for the form of the invention shown in Figures 1 to 6, inclusive, with the exception of the two following differences: First, the substitution of the conical point 110 for the ring 32 and, second, the elimination of the pin 67 and the substitution therefor of the contact members 107. The point 35 110 was substituted for the ring 32 with the thought that it might be advisable to eliminate the friction in the various rings and gimbals supporting the ring 32. The substitution of the contact members 107 for the pin 67 was made with the thought that it might be desirable to allow the sleeve 103 to rotate about the rod 104. If such rotation is not deemed necessary or advisable, the sleeve 63 of Figures 1 and 2 could be used in connection with the modification shown in Figures 7 to 10, inclusive.

35 In the modification of Figures 7 to 10, inclusive, the weight of the arms 102 below the axis connecting the bearing 101 to the sleeve 103 will tend by their own inertia to retard the movement of the sleeve 103 above the axis. The arms 102 could be of any desired length, even extending below the plane of the point of support. The arms 102 are adjustable to raise or lower the plane of the bearing 101 resting upon the point 97 to a plane above or below or identical to the plane of the gimbals 76, 77 and 78. By decreasing the thickness of the bearings 82 and 101, the points 110 and 97 may be brought to any desired proximity. On the other hand, the adjustable wires 86 may be shortened.

by means of the adjusting screws 95 to increase the distance between the points 110 and 97.

Here assume the points 110 and 97 are placed below the line of axis 21. By reason of the separation of the points 110 and 97 any tendency of change in the plane of the supporting gimbals caused by any change in the plane of the supporting platform 66 will cause friction between the points 110 and 97 and their respective bearings 82 and 101. Such tendency to change in the plane of the gimbals will tend to likewise cause the separate points 110 and 97 to revolve around their common center. The force would tend to cause the rod 104 and the sleeve 103 to move in the same directions, that is, in an upward arc with reference to the center of axis 21. The force would tend to cause the rod 104 to slip within the sleeve 103. The four points 107 on sleeve 103 would in such event be thrown against the rod 104 as said rod would tend to slip within said sleeve. This resulting force and friction counteracts the friction between the points 110 and 97 and their respective bearings 82 and 101 to maintain the rod 104 in a substantially vertical position.

Additional contact points 107 could be used to assist in promoting an equal amount of friction between the upper sleeve 103 and the rod 104 regardless of the direction from which a diverting force may be applied. In order to avoid binding, the contact points 107 could be spring cushioned. For the purposes of diminishing friction ball bearings could be substituted for the contact members 107.

Referring to the modification shown in Figure 11, four arms 117 are attached to a ring 118 not closely fitted around 123 and one end portion of each arm 117 is secured to a partial sphere 119 and the opposite end of each arm 117 is adapted to be attached to the ring 34 of the modification shown in Figures 1 to 6 or is adapted to be attached to the arms 102 of the modification shown in Figures 1 to 10, inclusive. (In liquid adaptation 119 could be made as a float).

The partial sphere 119 is disposed within a well 120 formed in the upper end portion of a rod 121 and has an external diameter substantially the same as the internal diameter of the well so that the outer surface of the partial sphere will contact the inner surface of the wall of the well 120. A rod 123 supports on its upper end a platform 124 and the rod 123 extends downwardly through centrally located passageway 125 of the partial sphere 119. The lower end portion of the rod 123 extends downwardly beyond the partial sphere 119 and has its end portion screw threaded as at 126. The threaded portion 126 is received by a threaded socket 127 in the rod 121 which communicates with the well 120.

In the use of the form of the invention shown in Figure 11, the limitation on the pendulous action of the rod 121 is similar to that described in connection with the form of the invention shown in Figures 1 to 6. (In liquid adaptation 119 would operate as an effective damping device).

Referring to the modification shown in Figure 12, this modified form is used when it is desired to diminish the size of sphere 129. Ring 130 would make contact with the inner wall of the well 120 of the rod 121. For this purpose the outside diameter of the sphere 129 is less than the inside diameter of the well 120 and the non bind ring 130 of the required thickness would

make contact with the inner wall of the well 120 and when the attachments are moved it would offer less resistance to the inner wall, that is, it would contact the wall at only two points.

5 In cases of modification in Figures 11 and 12, the spheres carry within them a weight, or weights could be made disposed along 117.

For the purpose of achieving added stability by a dampening device, the entire device as embodied either in the modifications shown in Figures 1 to 6 or 7 to 10, and 11 and 12 could be encased in liquid except for gimbal 20.

15 The reaction of ring 130 and sphere 129 to liquid would result in a damping effect. Assume that rod 123 and 117 are at their vertical positions. The instant force would be exerted on 117 and attachments and hydraulic effect would take place in well 120 due to the action of 130 and 129. The inertia of liquid of 123 and its attachments and resistance and friction at conical point 118 would offer resistance to moment of 117 and attachments partly due to resistance at pin 97. 117 and attachments would tend to lift 123 and attachments and carry them against bearing 82 at 110. If 117 and attachments would move in a direction away from 123, ring 130 would leave the horizontal permitting passage of liquid between 130 and the well casing lessening the hydraulic effect due to liquid. Turning of 130 and 129 would rotate the liquid in the well. The weight of 123 and attachments and 117 and attachments would return them to their original positions as the motivating force subsides. Holes in well casing below 129 and 130 would alter the damping effect of the operation described above. It is not believed that sufficient force would be transmitted through the gimbals to materially force 123 and attachments and 117 and attachments from their original vertical positions.

30 Referring to Figures 13 and 14, an outer spherical casing 131 is attached to the gimbal 23 and an inner spherical casing 132 is attached to the gimbal 25. The inner and outer casings 131 and 132 contain fluid which are in communication with one another through an opening 133 in the inner casing 132. Flanges 134 are supported by a rod 135 for minimizing the movement of the liquid between the outer and inner casings. The rod 135 is a prolongation of the rod 36 and its connections and extend through a suitable opening at the top of the outer casing 131 downwardly through the opening 133 of the inner casing 132. A float 136 is carried by the rod 36 and is disposed within inner casing 132. The inner casing 132 has openings 132a through which the arms 28 extend. In the case of the liquid modification of Figures 13 and 14 of the drawing, the modifications shown in Figures 11 and 12 could be employed in lieu of the sleeve 63 of Figures 13 and 14 by securing a float to the rod 123. The reaction of sleeve 63 and skirt 38 to liquid would result in a damping effect.

35 In the modification of the invention illustrated in Figures 7 to 10, the rod 135 would be screwed into the head of the rod 104 and in the case of the modifications shown in Figures 11 and 12, the rod 135 would be substituted for the rod 123.

40 In the use of the modification shown in Figures 13 and 14, all of the functions above described would take place. However, any tendency of the rod 136 to leave the vertical would be further discouraged by the buoyant action of the floats 136 and 129. It would reduce friction at the bearing point of rod 36. (As buoys 125 and 129

11

would have a lifting effect to reduce friction at 101.) In the case of Figure 12 movement of 117 would move ring 130 permitting an opening along the well of the wall, four openings in cylinder below 130 might be advisable. Moreover, any tendency towards rotation of the liquid caused by any surface friction within the casings 131 and 132 would be resisted by the float or floats. The float could be made adjustable so that it could be raised or lowered to regulate the action desired. The action of the liquid would assist in damping out vibration or oscillation within the device.

Fins 33a and 36d, respectively, protruding from sleeve 63 and rod or cylinder 36, would tend to further stabilize the device and prevent movement of the sleeve 63 and/or the rod or cylinder 36.

The modifications illustrated in Figures 15 to 18, inclusive, will cushion the device from shock caused by a sharp change in the direction of the supporting platform 139 when the device is used on a ship, an airplane or other moving object. The outer gimbal 20 or 76 is mounted either from the smallest of a series of three vertical half rings as shown in Figures 15 and 16 or from the smallest of a set of three vertical full rings as shown in Figures 17 and 18.

Referring more particularly to Figures 15 and 16, the outer gimbal 20 is mounted in the following manner: A shaft 137 has its lower end portion fitted into a bearing 138, mounted in a supporting platform 139. The upper end portion of the shaft 137 is secured to the bottom of a vertically disposed half ring 140, the upper end portions of which support bearings 141. The half ring 140 has one end of each of a pair of shafts 141a connected thereto and the opposite end of each shaft 141a is received by the respective bearing 141.

A full horizontally disposed ring 142 which is in the same horizontal plane as the outer gimbal 20 or 76 and the inner gimbals 23 and 25 or 77 and 78 is supported by the bearings 141. The ring 142 has mounted thereon bearings 143 which are spaced from the bearings 141 about 90 degrees. Shafts 144 each have one end portion mounted in a respective bearing 143 and its opposite end connected to a vertically disposed half-ring 145 having at its bottom a bearing 146 through which extends a rod 147 connected to the bottom of a vertically disposed half-ring 148. The lower end portion of the rod 147 is threaded and receives an adjustable screw threaded weight 149.

The half-ring 148 has mounted on its upper free ends bearings 150 into which fit, respectively, one end portion of each of shafts 151. The opposite end portion of each shaft 151 is connected to the outer gimbal 20 or 76 which supports the remaining parts of the device in the manner previously described. The half-rings 145 and 148 are disposed at an angle of 90 degrees to the half-ring 140.

Figures 17 and 18 show a modified form of the invention identical to that of Figures 15 and 16 except that the half-rings 140, 145 and 148 are made as full rings 140a, 145a and 148a, a standard 152 is mounted on the supporting member 139 and its upper end portion 153 is arcuate extending inwardly above the ring 140a. The free end of the portion 153 supports a bearing 154 which receives the upper end portion of a shaft 155, the lower end of which is connected to the ring 140a. The half-rings or full rings will act

12

as gimbals. The vertical gimbals would assist in damping or preventing rotation of the inner mechanism.

In order to insure the equivalent of a constantly moving platform, even while the ship, airplane or other platform is at rest, and to prevent static friction on resumption of motion by the platform, the whole device should be kept in slight motion at all times by a powered oscillator or by other convenient means.

The improved device would serve as a level for such instruments as gyros, magnetic and gyro-compasses, transits and theodolites. It would serve as a level platform for liquid containers such as to support compasses on ships and planes. It would furnish a level for guns or gunnery sights. It could be used in connection with an automatic pilot, bombsight, and alarm units aboard ships.

It will be noted that ball 69, Figure 2, could be constructed with a ring as number 129 and 130 of Figure 12 and that four holes could be placed beneath 69, in which case it would operate with reference to the description pertaining to operation described in Figure 12.

It is obvious that various changes and modifications may be made in the details of construction and design of the above specifically described embodiment of this invention without departing from the spirit thereof, such changes and modifications being restricted only by the scope of the following claims.

What I claim is:

1. An improved stabilized level support comprising at least two interconnected gimbals, a platform, a rod for supporting said platform, a yieldable supporting connection between said rod and one of said gimbals, a weight attached to said rod below its point of support, and an equalizing weight disposed above the point of support of said rod for equalizing said first weight and supported by the other of said gimbals.

2. An improved stabilized level support as claimed in claim 1 characterized by the fact that said yieldable supporting connection comprises a bearing supported by the said one gimbal and a conical member supported by said bearing and connected to said rod.

3. An improved stabilized level support as claimed in claim 2 characterized by the fact that said bearing is supported by wires and that a spool is provided for shortening and lengthening said wires for raising and lowering said bearing.

4. An improved stabilized level support as claimed in claim 3 characterized by the fact that said spool is mounted on a skirt and that said skirt is supported by arms which are connected to said gimbals.

5. An improved stabilized level support comprising a plurality of gimbals, a platform, a rod for supporting said platform, a yieldable supporting connection between said rod and one of said gimbals, a weight attached to said rod below its point of support, an equalizing weight disposed above the point of support of said rod for equalizing said first weight and supported by another of said gimbals, the upper end portion of said rod having a bore therein, a pin extending through said equalizing weight and having a portion received by said bore, and a ball detachably mounted on said portion of the pin and received by said bore.

6. An improved stabilized level support comprising a gimbal, a support for said gimbal, a

supporting member supported by said gimbal, a platform mounted on said supporting member, a weight attached to said supporting member below the point of support of said supporting member, a second gimbal rotatably supported by said support, a ring, arms connected to said second gimbal, an adjusting screw mounted on said arms, wires each having one end portion wound around said adjusting screw and its opposite end connected to said ring for raising and lowering said ring upon turning of said adjusting screw, and a weight disposed above the point of support of said supporting member for equalizing said first weight and supported by said ring for adjustable movement therewith.

7. An improved stabilized level support comprising a plurality of gimbals, a rod, a supporting connection between said rod and one of said gimbals, a weight attached to said rod below its point of support, the upper end portion of said rod having a well therein, a partial sphere disposed within said well, a second rod extending downwardly through said partial sphere and supported by said first rod, a platform mounted upon said second rod, and arms connected to said partial sphere and to another of said gimbals.

8. An improved stabilized level support comprising a plurality of gimbals, a rod, a supporting connection between said rod and one of said gimbals, a weight attached to said rod below its point of support, the upper end portion of said rod having a well therein, a sphere disposed within said well and having an outside diameter slightly less than the inside diameter of said well, a band mounted on the outer surface of said sphere and engaging the inner wall of said well, a second rod extending downwardly through said sphere and supported by said first rod, a platform mounted upon said second rod, and arms connected to said sphere and to another of said gimbals.

9. An improved stabilized level support comprising a gimbal, a support for said gimbal, a supporting member supported by said gimbal, a platform mounted on said supporting member, a weight attached to said supporting member below the point of support of said supporting member, a weight disposed above the point of support of said supporting member for equalizing said first weight, a gimbal for supporting said second weight, an outer spherical casing supported by said first gimbal, and an inner spherical casing supported by said second gimbal, each of said casings containing fluid and enclosing said gimbals, said supporting member and said weights.

10. An improved stabilized level support comprising an outer gimbal, an inner gimbal supported by said outer gimbal, a second inner gimbal supported by said outer gimbal, a rod supported by one of said inner gimbals, a platform mounted on said rod, a weight attached to said rod below its point of support, an equalizing weight disposed above the point of support of said rod for equalizing said first weight and supported by the other of said inner gimbals, a supporting member, a shaft mounted on said supporting member, a vertically disposed half ring mounted on said shaft and having bearings thereon, a full horizontally disposed ring supported in said bearings and having bearings thereon, a second vertically disposed half ring mounted in the bearings on said full ring and having a bearing in its bottom, a second rod extending through the bearing in the bottom of

said second vertically disposed half ring, a third vertically disposed half ring connected to said second rod and having bearings thereon connected to said outer gimbal, and a weight mounted on said second rod.

11. An improved stabilized level support as claimed in claim 10 characterized by the fact that said half rings are full rings, that a standard is supported by the supporting member, that said standard carries a bearing, and that a shaft is fitted in said standard bearing and connected to the first vertically disposed ring.

12. An improved stabilized level support comprising a plurality of gimbals, a platform, a rod for supporting said platform, a yieldable supporting connection between said rod and one of said gimbals, a weight attached to said rod below its point of support, an equalizing weight disposed above the point of support of said rod for equalizing said first weight and supported by another of said gimbals, the upper end portion of said rod having a socket therein, a pin extending through said equalizing weight, and a ball detachably mounted on the lower end of said pin and received by said socket.

13. An improved stabilized level support as claimed in claim 12 characterized by the fact that retaining bearing means are disposed within said socket and engage the upper surface of said ball, that vertically extending slots are provided in the wall of said socket in said rod, and that adjusting screws extend through said slots and engage said retaining bearing means, whereby said retaining bearing means may be vertically adjusted within said socket and may be entirely removed therefrom.

14. An improved stabilized level support comprising a gimbal, a support for said gimbal, a supporting member supported by said gimbal, a platform mounted on said supporting member, a weight attached to said supporting member below the point of support of said supporting member, a weight disposed above the point of support of said supporting member for equalizing said first weight, a gimbal for supporting said second weight, brackets mounted on each of said weights and having elongated slots therein, bolts mounted on said brackets for adjustment in said slots, weights mounted on each bolt, locking means for holding each bolt in its adjusted position, each bolt having a threaded socket therein, and a weighted screw threadedly received by the socket of each bolt.

15. An improved stabilized level support comprising a plurality of gimbals, a platform, a rod for supporting said platform, a yieldable supporting connection between said rod and one of said gimbals, a weight attached to said rod below its point of support, an equalizing weight encircling said rod and having spaced apart point contact therewith and disposed above the point of support of said rod for equalizing said first weight, said yieldable supporting connection comprising a skirt supported by said one gimbal, a bearing supported by the skirt, and a conical member supported by said bearing and operatively connected to said equalizing weight to support said equalizing weight.

16. An improved stabilized level support comprising a gimbal, a support for said gimbal, a supporting member supported by said gimbal, a platform mounted on said supporting member, a weight attached to said supporting member below the point of support of said supporting member, a second weight disposed above the

2,672,312

15

point of support of said supporting member for equalizing said first weight, and a second gimbal for supporting said second weight, said gimbals being interconnected.

CHARLES J. DRUEDING. 5
